UNITED STATES PATENT OFFICE.

DENIS WILLIAM DALEY, OF PARKERSBURG, WEST VIRGINIA.

SUPPORT AND STAY FOR MOLDBOARDS USED FOR ONE SIDE OF CONCRETE WALLS.

1,149,636.

Specification of Letters Patent. Patented Aug. 10, 1915.

Application filed December 16, 1913. Serial No. 807,053.

To all whom it may concern:

Be it known that I, DENIS WILLIAM DALEY, a citizen of the United States, residing at Parkersburg, in the county of Wood and State of West Virginia, have invented new and useful Improvements in Supports and Stays for Moldboards Used for One Side of Concrete Walls, of which the following is a specification.

10 This invention generically appertains to mold forms for concrete construction but more particularly to the means of arranging the supports and stays thereof.

One object of this invention resides in 15 providing means for reducing to a minimum the cost of erecting a mold form for concrete walls, to be constructed contiguous to other walls or earth banks.

A further object resides in providing 20 means for quickly and conveniently removing and erecting the various sections comprising the form.

A still further object resides in the provision of a series of coöperating elements 25 which will permit of the lower sections of the form to be removed from the set or hardened portion of the wall, and utilized for constructing the upper portion thereof.

With these and other objects in view my 30 invention consists of certain novel details of construction, combination and arrangement of parts to be more particularly pointed out and claimed.

In the accompanying drawings in which 35 similar parts are indicated by corresponding reference characters, Figure 1 is a transverse vertical section illustrating a wall partially constructed, with the mold boards removed from the lower portion and in use on the upper portion thereof. Fig. 2 is a side elevation of a fragment of a wall with the lowermost mold boards removed, and illustrating the elements used in maintaining the latter in position. Fig. 3 is a top plan view 40 of a partially constructed wall showing a mold board attached. Fig. 4 is a detailed view of one member of my adjustable stay. Fig. 5 is a similar view of a modified form of one of my improved standards. Fig. 6 is 45 a perspective view illustrating my mold board supporting bracket. Fig. 7 is a side elevation of a tie rod.

In the illustrated embodiment, my invention contemplates the formation of a plurality of suitably spaced channels 1 in one 50 face of an embankment for the reception

of the standards 2. Said standards 2 are preferably formed of metal although it is to be understood that posts of wood or other suitable material may be used if found desirable. These posts or standards 2, are vertically disposed within channels 1, and have their lower extremities extended slightly below the ground surface, so that they may be firmly braced to withstand the lateral thrust of the poured concrete, while their upper extremities are extended a short distance above the upper surface of the embankment for engagement with the stays or anchoring irons 3, to permanently retain 70 said posts in adjusted position.

The anchoring irons 3 are formed in two sections 3' and 3'', each section having its outer extremity arcuate shaped as at 4 to partially circumscribe the posts 2, and its 75 opposite extremity enlarged and provided with the laterally projecting prongs 5 which, after the portions 4 of the anchor irons have been properly positioned upon posts 2, are driven into the upper surface 80 of the embankment so as to eliminate any lateral movement on the part of said posts 2.

In order to bring the arcuate shaped portions 4 into binding engagement with the standards or posts 2, the sections 3' and 3'' 85 are each provided contiguous to their arcuate extremities with a bolt opening 5, through which passes a headed bolt 6, having a threaded extremity to receive a nut 7, by means of which the arcuate shaped portions 4 may be caused to firmly grip the post 2, as will be apparent without further description.

As it may sometimes be necessary to adjust the sections 3' and 3'' after the latter 95 have been positioned, said sections are formed in two parts and provided with the adjusting nut 8 by means of which it is possible to increase or decrease the length of said sections without necessitating the 100 disengagement of the pronged extremities thereof.

To support the mold boards in proper horizontally spaced relation to the channeled face of the embankment a series of 105 vertically disposed angular stays 9 are offset from the latter, and relatively arranged in alined and spaced relation. The angular stays 9 correspond in length to the standards 2, they also have their lower extremities extended beneath the ground surface and their upper extremities engaged by

the anchoring irons 3, in the same manner as described in connection with the standards 2.

Mounted in alined and vertically spaced 5 relation upon the angle irons 9 are the brackets 10, each consisting of the supporting section or base 11, formed at one end with the oppositely projecting fingers 12, and at the other end thereof with the rectangular notch 13 having the flange 14 surrounding and depending therefrom to form a seat for one edge of said angular stays 9 and permit said bracket 10 to be disposed thereupon, with its supporting section 11, 15 project outwardly in a plane at right angles thereto, which it will be seen forms a shelf upon which the lower longitudinal edge of the mold boards may rest while the fingers 12, projecting in opposite directions overlie the abutting edges of said mold boards, thereby preventing the latter from being pushed outwardly by the lateral thrust of the cement. In this connection, it is to be noted that although the brackets 10 are 20 loosely disposed upon angle irons 9, nevertheless, owing to their particular conformation, when the mold boards are disposed upon the same, the weight of the latter will cause the outermost portion of the flange 14 to frictionally engage the angle iron and thus prevent slipping of said brackets as will be readily understood. The brackets 10 are arranged in alinement at predetermined points on the angular stays 9, the distance 25 between the brackets corresponding to the width of the mold boards, which latter are placed edgewise one above the other against the outer surface of said angle irons 9, with their lower edge resting on the supporting section 11 of the brackets as heretofore described, thus forming a unitary structure which coacts with the side of the embankment to produce a mold into which concrete 30 may be poured.

To further reinforce the mold boards standards 2, are provided with a series of laterally projecting studs 15. Tie wires or chains 17 are detachably connected at one extremity to the studs 15 and have their opposite extremities passed between the abutting edges of the mold boards, and through 35 an opening 18 formed in the plates 19 which latter are transversely disposed upon said mold boards at the meeting longitudinal edges thereof as clearly shown in Fig. 2. A pin 20 secured to the free ends of said tie wires or chains, prevents disengagement of the same, and at the same time allows them to be tightened to a more or less greater extent, inasmuch as revolving the pin 20 will 40 increase or decrease the tension upon said chains or wires as will be readily understood.

It may some times be desirable to employ 65 a tie rod in place of the chains or wires 17 in

which instances in lieu of the studs 15 on posts 2, I provide the latter with key slot openings 21, to receive the notched end of the rod 22, whose opposite end is threaded, extends through the opening 18 in plate 19, 70 and has a nut 23 engaged to retain said rod in position.

By connecting the tie rod 22 or chains 17 to the standard 2 in the manner specified, to remove said rod or chains it is simply necessary to partly revolve the standards 2 which will immediately disengage the notched ends of the tie rods from the key slots 21, or the studs 15 from tie chains 17, because if the chains are used the studs are passed through one of their links whereas on the other hand if wires are employed they are looped over the studs 15, so that in either case the chains, wires or rods will be released.

As a substitute for the post or standard 2, 85 I sometimes use an angular shaped post 24 which is placed in the channel 1 with its apex facing the mold boards to permit of its ready removal therefrom. This angular post has one wing formed with transverse slots 25 extending inwardly from its edge, which takes the place of the studs 15 on annular posts 2 and receives one extremity of the tie chains 17, the latter being held by pins 26. Hence by outwardly revolving the 95 post 24 within the channels, said post will become disengaged from the chains and consequently can be conveniently removed from said channels when necessary.

In view of the above description it will be 100 apparent that I have provided a series of coöperating elements by means of which it becomes possible to erect a mold form in offset relation to one face of an embankment or wall, whereby a wall of concrete or other 105 plastic substance may be erected contiguous to said embankment, said mold being formed in courses and having means by which the lower course may be removed from the hardened or set portion of the concrete and 110 positioned upon the uppermost course to form a further continuation of the mold and in this manner enable the same courses of the mold to be constantly reused in the construction of the wall as the latter progresses 115 upwardly.

Although by the foregoing description I have described certain elements as best adapted to perform the function ascribed to them nevertheless it is to be understood that 120 various minor changes in form, material, etc., may be resorted to within the scope of the appended claims without departing from or sacrificing any of the principles of this invention.

Having now described my invention what I claim is:

1. The herein described mold form for co-operation with one face of an embankment 125 consisting of a plurality of standards verti- 130

- 5 cally disposed in spaced relation in the face of said embankment, means for fixedly maintaining said standards in adjusted position, a plurality of spaced apart angular stays vertically disposed in offset relation to the face of said embankment, a plurality of brackets detachably connected to said stays and disposed in vertically spaced relation thereon, mold boards disposed edge-
wise upon said bracket whereby to produce a mold form, means on said brackets adapted to overlie the contiguous edges of said mold boards and prevent lateral movement thereof, reinforcing plates overlying the 10 abutting edges of said mold boards, and connections between said plates and said standards, the latter being detachably connected therewith substantially as and for the purpose set forth.
- 15 2. The herein described mold form for cooperation with one face of an embankment consisting of a plurality of standards vertically arranged in spaced relation in the face of said embankment, a series of alined angular stays disposed in offset relation to said standards, means for securing said standards and said stays in adjusted position, a plurality of brackets detachably secured in vertically spaced relation upon said stays, 20 said brackets including a mold board supporting section having oppositely projecting fingers at one extremity thereof, the other extremity being formed with a notch opening inwardly from one edge thereof, a flange surrounding said opening and projecting downwardly therefrom, said flange and notch coacting to form a seat for one edge of said angular stays, mold boards supported edgewise upon the mold board supporting section of said bracket, the fingers on the latter being adapted to overlie the abutting edges of said mold board and prevent lateral movement thereof, and connecting means between said mold board and said standards, said connecting means being detachably connected with the latter substantially as and for the purpose set forth.
- 25 3. The herein described mold form for cooperation with one face of an embankment consisting of a plurality of standards vertically disposed in spaced relation in the face of said embankment, a series of alined angular stays disposed in offset relation to said standards, anchoring irons engaged with the upper extremities of said standards and said stays, said anchoring irons including two members each of said members having one end arcuate shaped to engage said standards and stays, and formed with an opening contiguous the arcuate shaped portion thereof, the other end enlarged and formed with a depending prong adapted to be seated in said embankment, a headed bolt passing through the openings in said irons, 30 said bolt having its free end threaded, a nut engaging said threaded end whereby said arcuate shaped extremities may be brought into bending engagement with said standards and said stays, brackets disposed in alined and spaced relation upon said stays, 70 mold boards supported edgewise upon said brackets, and connecting means between said standards and said mold boards, said means being detachably connected with said standards substantially as and for the purpose 75 set forth.
- 35 4. The herein described mold form for cooperation with one face of an embankment consisting of a plurality of standards disposed in the latter, means for maintaining said standards in adjusted position, a plurality of stays offset from the face of said embankment, supporting brackets detachably secured to said stays, mold boards disposed edgewise upon said brackets, means 80 carried by the latter to overlie the contiguous edges of said mold boards, whereby to prevent outward lateral movement thereof, and detachable connecting means between said standards and said mold board, sub- 90 stantially as and for the purpose set forth.
- 45 5. The herein described mold form for cooperation with one face of an embankment, consisting of a plurality of standards disposed in the latter, means for maintaining 95 said standards in adjusted position, a plurality of suitably spaced angular stays vertically disposed in offset relation to the face of said embankment, supporting brackets detachably secured to said stays, mold 100 boards disposed edgewise upon said brackets, means carried by the latter to overlie the contiguous edges of said mold boards, whereby to prevent outward lateral movement thereof, and detachable connecting 105 means between said standards and said mold boards, substantially as and for the purpose set forth.
- 50 6. The herein described mold form for cooperation with one face of an embankment, 110 consisting of a plurality of standards disposed in the latter, means for maintaining said standards in adjusted position, a plurality of angular stays vertically disposed in offset relation to the face of said embankment and situated in alined and horizontally spaced relation, supporting brackets detachably secured to said stays, mold boards disposed edgewise upon said brackets, means carried by the latter to overlie 115 the contiguous edges of said mold boards, whereby to prevent outward lateral movement thereof, and detachable connecting means between said standards and said mold boards, substantially as and for the purpose 120 set forth.
- 55 7. The herein described mold form for cooperation with one face of an embankment consisting of a plurality of standards vertically disposed in spaced relation in the face 125

- of said embankment, means detachably engaged with the upper extremities of said standards for maintaining the latter in adjusted position, a plurality of spaced angular stays vertically disposed in offset relation to the face of said embankment, a plurality of brackets detachably connected to said stays and disposed in vertically spaced relation thereon, mold boards disposed edgewise upon said brackets, whereby to produce a mold form, means on said brackets to overlie the contiguous edges of said mold boards and prevent lateral movement thereof, reinforcing plates overlying the abutting edges of said mold boards, and connections between said plates and said standards, the latter being detachably connected therewith, substantially as and for the purpose set forth.
- 10 8. The herein described mold form for co-operation with one face of an embankment consisting of a plurality of standards vertically disposed in spaced relation in the face of said embankment, anchoring irons having one of their extremities co-operating with the upper end of said standards, the other extremity of said irons being engaged with said embankment, whereby said standards are maintained in adjusted position, a plurality of spaced angular stays vertically disposed in offset relation to the face of said embankment, a plurality of brackets detachably connected to said stays and disposed in vertically spaced relation thereon, mold boards disposed edgewise upon said brackets whereby to produce a mold form, means on said brackets to overlie the contiguous edges of said mold boards and prevent lateral movement thereof, reinforcing plates overlying the abutting edges of said mold boards, and connections between said plates and said standards, the latter being detachably connected therewith, substantially as and for the purpose set forth.
- 15 9. The combination with a mold form for co-operation with one face of an embankment, said form including a plurality of standards, of means for maintaining said standards in adjusted position comprising a plurality of anchoring irons, each of the latter including two members, each of which has one extremity arcuate shaped to partially circumscribe said standard and the other extremity provided with a depending prong adapted to be seated in said embankment, and means in connection with said members whereby the arcuate shaped portions of the latter may be brought into binding engagement with said anchoring irons, substantially as and for the purpose set forth.
- 20 10. The combination with a mold form for co-operation with one face of an embankment, said form including a vertical standard, of means for maintaining said standard in adjusted position comprising an anchoring iron, the latter consisting of a pair of angularly disposed members, each of said members having its outer end arcuate shaped, the other end enlarged and formed with a depending prong adapted to be seated in said embankment, and means in connection with said members whereby the arcuate shaped portions thereof may be brought into binding engagement with said anchoring iron, substantially as and for the purpose set forth.
- 25 11. The combination with a mold form for co-operation with one face of an embankment, said form including a plurality of standards, of means for maintaining said standards in adjusted position comprising a plurality of anchoring irons, each including two members, each of said members having one end arcuate shaped to engage said stand-

ards and formed with an opening contiguous to the arcuate shaped portion thereof, the other end enlarged and provided with a depending prong adapted to be seated in said embankment, a headed bolt passing through the openings in said irons, said bolt having its free end threaded, a nut engaged with said threaded end, whereby said arcuate shaped extremities may be brought into binding engagement with said standards, substantially as and for the purpose set forth.

30 12. The combination with a mold form for co-operation with one face of an embankment, said form including a plurality of standards, of means for maintaining said standards in adjusted position comprising a plurality of anchoring irons, each of the latter including two members, each of which has one extremity arcuate shaped to partially circumscribe said standard and the other extremity provided with a depending prong adapted to be seated in said embankment, and means in connection with said members whereby the arcuate shaped portions of the latter may be brought into binding engagement with said anchoring irons, substantially as and for the purpose set forth.

35 13. The combination with a mold form for co-operation with one face of an embankment, said form including a vertical standard, of means for maintaining said standard in adjusted position comprising an anchoring iron, the latter consisting of a pair of angularly disposed members, each of said members having its outer end arcuate shaped, the other end enlarged and formed with a depending prong adapted to be seated in said embankment, and means in connection with said members whereby the arcuate shaped portions thereof may be brought into binding engagement with said anchoring iron, substantially as and for the purpose set forth.

In testimony whereof, I affix my signature in presence of two witnesses.

DENIS WILLIAM DALEY.
